8 Claims. (Cl. 102—49)

(Granted under Title 35, U.S. Code (1952), sec. 266)

This invention relates to a rocket, and more specifically to a cluster rocket adapted to be launched from an aircraft in flight or from a ground position, as the case may be, and fire on land or water impact.

The present type rockets now in use by the armed forces are provided with a single rocket motor and a main explosive charge in which means such as a firing pin, spring and other parts are necessary to fire the center primer when the rocket strikes a target thereby to fire the main explosive charge. This invention contemplates the use of a single motor and a plurality of auxiliary explosive charges releasably nested around the motor and adapted to be fired by a rim firing primer in predetermined time delayed relation with respect to the impact of the rocket with the target. This arrangement eliminates the use of the aforesaid firing pin, spring and other parts and saves time, labor and material inasmuch as only a single motor is used to impel the plurality of explosive charges toward the target. Furthermore, the rocket of the present invention is constructed in such a manner as either to concentrate the entire plurality of charges on the target or to release the charges upon impact of the rocket with the target and thereby scatter the charges over a wide area.

More specifically, the invention relates to a cluster rocket in which a plurality of auxiliary explosive filled containers are locked to the rocket body until the rocket strikes the target whereupon the containers are released therefrom and exploded when a predetermined period of time has elapsed.

One of the objects of the present invention is to produce a new and more powerful and destructive rocket in which a single motor is utilized to impel a plurality of auxiliary explosive charges toward the target.

Another object is the provision of a new and improved rocket having an explosive filled container and a plurality of auxiliary explosive filled containers locked thereto and adapted to be released upon impact of the rocket with the target in which firing of the explosives will occur a predetermined period of time after the impact.

Another object is the provision of a new and improved rocket having a plurality of auxiliary explosive charges secured thereto and adapted to be released upon impact of the rocket with the target thereby to scatter the charges over the target area indiscriminately, and in which the firing thereof may be delayed a predetermined period of time such, for example, as from 0 seconds to 20 seconds.

A still further object is to provide a new and improved cluster rocket which is economical to manufacture, reliable in operation and which possesses all the qualities of ruggedness and dependability in service.

2

Still other objects, advantages and improvements will be apparent from the description, taken in connection with the accompanying drawings, of which:

Fig. 1 is an end view of the cluster rocket constructed in accordance with the present invention;

Fig. 2 is a central longitudinal sectional view of the cluster rocket taken on line 2—2 of Fig. 1;

Fig. 3 is a view similar to Fig. 2 but showing the outer rocket bodies locked in position in such a manner as to concentrate the entire charge upon the target; and

Fig. 4 is a transverse sectional view taken on line 4—4 of Fig. 2.

Referring now to the drawings for a more complete understanding of the invention, the cluster rocket comprises a motor tube 10 having a motor generally indicated by the reference character 11 arranged therein. The motor 11, Fig. 2, is a conventional type of rocket motor and includes the usual rocket motor components such, for example, as a propellant 12, grid 13 for supporting the propellant within the tube 11, nozzle 14 adapted to direct the gas jet in the desired direction as the propellant burns and also provides for expansion of the gases in the exit cone of the nozzle, igniter 15 having an igniter charge 16 arranged therein adapted to ignite the propellant, a squib 17 arranged within the igniter, conductors 18 secured to the squib and adapted to supply an electrical impulse thereto when the rocket is launched and fire the squib thus igniting the igniter charge which in turn ignites the propellant.

The motor tube 10 has secured to one end thereof the usual stabilizing assembly generally indicated by the reference character 19 comprising a plurality of fins 21, the fins being secured to the tube in any suitable manner and extending radially therefrom and having a shroud 22 secured to the outer portions thereof. It will be understood, however, that the stabilizing assembly may be utilized to provide contacts for firing the squib when the rocket is launched. Therefore, as the operation and structure of rocket motors are well known to those skilled

in the art, further detail description of the operation and structural arrangement thereof is deemed unnecessary in view of the fact that a conventional type of rocket motor is used.

Threaded to the other end of the motor tube 10 as at 23 is a cup-shaped member 24 having an end wall 25 integrally formed thereon. A center rocket body generally indicated by the reference character 26 and comprising a cylindrical casing 27 is secured to the cup-shaped member 24 in any suitable manner such, for example, as by threading two parts together at 28. The other end of the casing 27 is internally threaded as at 29 and having threaded engagement with a relatively thick disc 31, the disc 31 being threaded into the casing a predetermined distance thereby to provide means for also threading a center retaining head generally indicated by the reference character 32 to the end of the casing, Fig. 2.

As shown on Fig. 2, an explosive charge 33 of T.N.T. or the like is arranged within the casing 27 between the disc 31 and end wall 25 formed on the cup-shaped member 24 thereby maintaining the charge in fixed position within the casing.

A plurality of auxiliary outer rocket bodies 20 are releasably nested around the center rocket body 26, Fig. 2, the bodies comprising a casing 34, one end thereof being closed by a disc 35 secured thereto in any suitable manner, preferably by welding the parts together, the other end thereof being closed by a disc 36 having threaded engagement with the casing and adapted to be threaded a predetermined distance therein such that an outer rocket head generally indicated by the reference character 37 may also be threaded into the end of each casing 34. An explosive charge 38 such, for example, as T.N.T. or the

like is arranged within each casing 34, the discs 35 and 36 being provided to maintain the charges in fixed position within the casing.

The discs 31 and 35 are provided with centrally disposed threaded bores 39 extending therethrough, having threaded therein delay housings or tubes 40, one end of the housings extending a predetermined distance into the explosive charges 33 and 38, the other ends of the housings extending a predetermined distance beyond the discs 31 and 36, Fig. 2.

A starter composition 41 is arranged in one end of each housing 40, the starter composition having abutting engagement with a time delay composition 42, the delay composition being adapted to be fired by the starter composition upon impact of the rocket with the target thereby to fire the charges 33 and 38 a predetermined time after impact of the rocket with the target, such time delay period being varied from 0 seconds to 20 seconds if desired.

The heads 32 and 37 are provided with end walls 43 having centrally disposed openings formed therein and adapted to support rim firing primers 44 in operative relation with respect to the starter composition 41. The rim firing primers are conventional type and adapted to be fired in the usual manner, therefore further detailed description thereof is deemed unnecessary.

The outer rocket bodies 20 are releasably supported on the center rocket body 26 in any suitable manner but preferably by a spider generally indicated by the reference character 45 and by a plurality of lugs 46 formed on the center rocket head 32, Fig. 2. The spider comprises a plurality of arms 47 extending radially from a hub 48 slideably arranged on the motor tube 10, the spider being adapted to move to a release position upon impact of the rocket with the target. Each arm 47 is provided with a convex button or lug 49 secured thereto as at 51 and adapted to seat in a concave well 52 formed in the end wall 35 of each of the outer rocket bodies, the buttons being urged into engagement with the wells 52 by a spring 53, one end thereof engaging the hub 48 on the spider 45, the other end thereof engaging a rear guide member 54 adjustably supported on the tube 10.

As shown on Fig. 2, one of the plurality of lugs 46 is adapted to engage a flange 55 formed on each outer head 37, the flange being maintained in locking engagement with the lug by the aforesaid spring 53. Thus with the guide member 54 clamped in the position shown on Fig. 2, the outer rockets 20 are releasably locked to the center body 26 and will remain locked thereto until the rocket strikes the target. When this occurs the deceleration of the rocket as it strikes the target will force the outer rocket bodies 20 rearwardly against the tension of the spring 53 in such a manner as to release the flanges 55 from the lugs 46 and concurrently therewith the spring is contracted. When the deceleration has decreased sufficiently the now released outer rocket bodies will be dispersed about the target area, it being understood, however, that the rim firing primers are fired upon the initial impact.

As shown on Fig. 2, a complementary guide member 56 similar to the guide member 54 is secured to the head 32 as by screw 57. The guide members 54 and 56 are adapted to support and guide the rocket in the rocket launching rack during launching operation.

As shown on Fig. 3, the outer rocket bodies 20 are locked to the center body 26 by the guide member 54 and will remain locked thereto upon impact of the rocket with the target such that the explosions of the entire plurality of charges contained within the rocket bodies are concentrated, thus increasing the destructibility of the rocket over rockets previously used by the armed forces in which a single explosive charge is employed. It will be understood, however, that when the outer rocket bodies are desired to be locked permanently to the center rocket body, the screw 58 for clamping the rear guide 54 to the

motor tube 10 is unscrewed sufficiently to release the guide from the tube and to permit sliding movement of the guide along the tube whereupon the guide is forced toward the spider 45 against the tension of the spring 53 until the spring is fully contracted, Fig. 3. When this has been accomplished, the screw 58 is tightened in such a manner as to lock the guide to the tube thereby to prevent movement of the spider with respect to the guide upon impact of the rocket with the target. Therefore it will be apparent from the above description that the outer rocket bodies are permanently locked between the spider 45 and head 32 by the aforesaid buttons and lugs and upon impact of the rocket with the target the entire explosive force of the rocket bodies are concentrated on the target.

The operation of the device will now be described. Let it be assumed by way of example, that the rocket is launched from a ground position although, of course, it could have been launched from an aircraft in flight, it being understood, however, that the rocket is releasably supported on the launching rack by the front and rear guides 54 and 56. When the squib 17 is fired by an electrical impulse supplied thereto through the conductor wires 18 from any suitable source of power such, for example, as a battery (not shown), the igniter charge 16 is fired, whereupon the propellant 12 of the motor is ignited by the igniter charge and thus the rocket is impelled from the launching rack toward the target as the propellant burns. When the rocket strikes the target the force of impact with the target will fire the rim firing primers 44 supported in the rocket bodies 20 and 26 and concurrently therewith the outer rocket bodies are moved rearwardly against the tension of the spring 53 in such a manner as to disengage the flanges 55 on the outer rocket bodies from the lugs 46 on the head 32, and the spring 53 recoils, the outer rocket bodies are dispersed over the target area and are fired when a predetermined period of time has elapsed, such time delay period being controlled by the time delay elements respectively arranged in each rocket body.

Should it be desired to concentrate the entire explosive force of the rocket bodies on the target, the rear guide 54 is moved to the position shown on Fig. 3 thus permanently locking the outer rocket bodies to the center rocket body thereby to permit simultaneous firing of the rocket bodies in response to impact thereof with the target.

From the foregoing description it will be understood that means are provided whereby a plurality of outer rocket bodies are driven through the air by a single rocket motor and are releasably locked to the main rocket body and will remain locked thereto until impact of the rocket with the target, whereupon the outer rocket bodies are automatically released from the main rocket body upon impact of the rocket with the target thereby to disperse the outer rocket bodies over the target area, the inner and rocket bodies being provided with time delay elements adapted to fire the explosive charges arranged within each rocket body in predetermined time delayed relation with respect to impact of the rocket with the target, and in which means are also provided for concentrating the entire explosive force of the rocket bodies on the target, if desired.

While the invention has been described with reference to a rocket having high explosive charges arranged therein for destructive purposes, it will be understood, however, that if desired the rocket bodies may be provided with pyrotechnic mixture such, for example, as the type now used in signalling devices, smoke emitting devices and the like.

While the invention has been described with reference to a particular example thereof which give satisfactory results, it will be obvious to those skilled in the art to which the invention pertains, after understanding the invention, that various changes and modifications may be made without departing from the spirit and scope of the invention,

and it is my intention therefore, in the appended claims to cover all such changes and modifications.

The invention herein described and claimed may be manufactured and used by or for the Government of the United States of America for governmental purposes without payment of any royalties thereon or therefor.

What is claimed as new and desired to be secured by Letters Patent of the United States is:

1. A cluster rocket having a motor adapted to impel the rocket from a launching rack toward a target, means on said rocket for supporting the rocket in said launching rack and guiding the rocket therefrom as the motor is set in operation, a main casing secured to said motor and having an explosive charge arranged therein, a plurality of auxiliary casings having opposite ends thereof adaptable to be releasably secured to said main casing, a plurality of explosive charges respectively arranged within said auxiliary casings, lug and spring actuated spider means engaging said opposite ends for releasably securing the auxiliary casings to said main casing until impact of the rocket with the target, and means for firing said explosive charges in predetermined time delayed relation with respect to said impact.

2. A cluster rocket having a motor adapted to impel the rocket from a launching rack and through the air toward a target, a pair of members secured to said rocket for supporting the rocket in said launching rack and guiding the rocket therefrom as the motor is set in operation, a main casing secured to said motor, an explosive charge arranged within said main casing, a plurality of auxiliary casings having opposite ends thereof adaptable to be releasably secured to said main casing, a plurality of explosive charges respectively arranged within said auxiliary casings, lug means and spider means engaging said opposite ends for releasably securing the auxiliary casings to said main casing, spring means on said main casing in engagement with one of said supporting members and the spider means for maintaining said lug means and spider means in engagement with said opposite ends until impact of the rocket with the target, and means for firing said explosive charges in predetermined time delayed relation with respect to said impact.

3. A cluster rocket having a motor adapted to impel the rocket from a launching rack and through the air toward a target as the motor is set in operation, a main casing secured to said motor, a pair of members secured to said motor and casing respectively for supporting the rocket in said launching rack and guiding the rocket therefrom when the motor is set in operation, an explosive charge arranged within said casing, a plurality of auxiliary casings circumferentially and releasably arranged on said main casing, a plurality of explosive charges respectively arranged within said auxiliary casings, means including a plurality of lugs for maintaining the auxiliary casings circumferentially and releasably on the main casing until impact of the rocket with the target, and means including a plurality of rim firing primers for firing said explosive charges in predetermined time delayed relation with respect to said impact.

4. A cluster rocket of the character disclosed adapted to be launched from a launching rack and comprising an elongated casing, a motor arranged within said casing for impelling said rocket from said rack and through the air toward a target, a pair of members on said rocket for guiding the rocket from said rack when the rocket is set in motion, an explosive inner container in alignment with and secured to said casing, a plurality of auxiliary explosive containers disposed about and releasably secured to said inner container, a flange portion secured to one end of said auxiliary containers respectively, a plurality of lugs on one end of said inner container in locking engagement with said flange portions, a spider slideably arranged on the casing, a plurality of buttons on said spider in locking engagement with the other ends of said auxiliary containers, means on the casing and having one end in engagement with one of said guide members and the

other end thereof in engagement with said spider for releasably maintaining said lugs in locking engagement with said flange portion and said buttons in locking engagement with said other ends of said auxiliary containers until impact of the rocket with the target, a plurality of time delay elements arranged within said containers respectively, and a plurality of rim firing primers arranged within said containers in alignment with said delay elements for firing said delay elements thereby to fire said explosive containers in time delayed relation with respect to impact of the rocket with the target.

5. A cluster rocket comprising an elongated casing, a motor arranged within said casing and adapted to impel the rocket from a launching rack and through the air toward a target when the motor is set in operation, a main container secured to said casing in alignment therewith, a plurality of lugs secured to one end of said casing, an explosive charge arranged within said container, a plurality of auxiliary containers releasably secured to said container, a plurality of flange members respectively disposed within one end of said auxiliary containers in engagement with said lugs, a plurality of explosive charges respectively arranged within said auxiliary containers, a spider slideably arranged on said casing and normally in locking engagement with the other end of said auxiliary containers and adapted to coact with said flange members and lugs for releasably locking the auxiliary containers to the main casing, a spring disposed about the casing in engagement with said spider for releasably maintaining the auxiliary containers locked to the main container and adapted to release the auxiliary containers upon impact of the rocket with the target, and means including a plurality of rim firing primers arranged within said containers for firing said explosive charges in predetermined time delayed relation with respect to said impact.

6. A cluster rocket having a motor adapted to impel the rocket from a launching rack and through the air toward a target as the motor is set in operation, a housing for said motor, a main casing secured to said housing in alignment therewith, a pair of guide members secured to said housing and casing respectively for guiding said rocket from said rack, an explosive charge arranged within said casing, a plurality of auxiliary casings circumferentially and releasably arranged on said main casing, a plurality of explosive charges respectively arranged within said auxiliary casings, a plurality of end walls respectively arranged on said auxiliary casings, each of said end walls having a recess formed therein, a member slideably arranged on said motor housing and having a plurality of arms extending radially therefrom, a plurality of buttons respectively arranged on said arms in engagement with said recesses respectively, lug means on said main casing in engagement with said auxiliary casings respectively at the opposite ends thereof with respect to said buttons and adapted to coact with said buttons for releasably locking said auxiliary casings to said main casing, a spring arranged about said housing and having one end in engagement with one of said guide members and the other end thereof in engagement with said slideable member for maintaining the auxiliary casings locked to said main casing until impact of the rocket with said target, and means including a plurality of rim firing primers respectively arranged in said casings for firing said explosive charges in time delayed relation with respect to said impact.

7. A cluster rocket having a motor adapted to impel the rocket from a launching rack and through the air toward a target as the motor is set in operation, a motor housing, a main casing secured to said motor housing and having an explosive charge therein, a plurality of auxiliary casings releasably locked to said main casing, means including a plurality of lugs and buttons carried by said main casing in engagement with said auxiliary casings for releasably locking said auxiliary casings to

the main casing until impact of the rocket with said target, a plurality of explosive charges respectively arranged in said auxiliary casings, a guide member secured to said main casing, a complementary guide member on said motor and adapted to coact with said first named guide member for guiding the rocket from said rack, means on said last named guide member for controlling the degree of dispersion of said auxiliary casings as the rocket strikes the target, and means including a plurality of delay elements respectively arranged within said auxiliary casings for firing said explosive charges in predetermined time delay relation with respect to impact of the rocket with said target.

8. A cluster rocket having a motor adapted to impel the rocket from a launching rack and through the air toward a target as the motor is set in operation, a housing for said motor, a main casing secured to said housing in alignment therewith and having an explosive charge arranged therein, a plurality of auxiliary casings releasably locked to said main casing, means including a plurality of lugs and buttons carried by said main casing in engagement with said auxiliary casings for releasably locking said auxiliary casings to the main casing until impact of the rocket with said target, a plurality of explosive charges respectively arranged in said auxiliary

casings, means including a plurality of delay elements respectively arranged within said auxiliary casings for firing said explosive charges in predetermined time delayed relation with respect to impact of the rocket with said target, a guide member secured to one end of said main casing, a complementary guide member slideably arranged on said housing and adapted to coact with said first named guide member for guiding the rocket from said rack when said motor is set in operation, and means including a member in threaded engagement with said last named guide member for locking the guide member to the housing and the auxiliary casings to the main casing for controlling the degree of dispersion of the auxiliary casings as the rocket strikes the target.
